[57] CLAIM

The ornamental design for a lighting fixture, as shown and described.

DESCRIPTION

FIG. 1 is a side elevational view of a lighting fixture showing our new design, all sides being identical;

FIG. 2 is a top plan view thereof;

FIG. 3 is a bottom plan view thereof;

FIG. 4 is a fragmentary side elevational view thereof, the side being cut away to show the interior lights.

Alternating rectangular panels of the fixture are shaded with oblique lines to indicate translucency. The remaining rectangular panels are transparent.
